CAMERA SHUTTER, INCLUDING ADJUSTABLE FLASH SYNCHRONIZING MEANS

Carl C. Fuerst, Rochester, N. Y., assignor to Eastman Kodak Company, Rochester, N. Y., a corporation of New Jersey

Application September 7, 1949, Serial No. 114,375

8 Claims. (Cl. 95—11.5)

1

The present invention relates to a flashlight synchronizing mechanism built into a photographic shutter, and particularly to a synchronizing mechanism of this type in which the time delay between closing of the lamp circuit and opening of the shutter is automatically adjusted to give the best possible light and speed combination for any speed setting of the shutter.

Conventional non-repetitive flashlamps are available in several types, the types generally being distinguished by the burning characteristics of the lamps. So far as the present invention is concerned, the only two types of lamps of interest are the type having substantially a 20-22 millisecond "lag," and the type having substantially a 5 millisecond "lag." The first-mentioned type of flashlamp produces a higher peak illumination than the other and has a light curve extending over a much greater time duration, as will be set forth in more detail hereinafter. In other words, the lamps with a 20-22 millisecond "lag" come to peak illumination more gradually, having a wider peak, and die out more gradually than lamps having a 5 millisecond "lag." Flashlamps having a 20-22 millisecond "lag" characteristic include those on the market and designated as types #5, #11, #25, #40, #42, etc.; these number designations being used by different lamp manufacturers.

Lamps having a 5 millisecond "lag" characteristic include the SM flashlamp manufactured by General Electric Company. In order to readily identify these different types of flashlamps according to their burning characteristics without referring to manufacturers' trade numbers, the A. S. A. has set up specifications grouping these different types of flashlamps according to classes. According to A. S. A. Specification "Z"-52.43-1944 all non-repetitive flashlamps having substantially a 20-22 millisecond "lag" and the wide characteristic light curve, are designated as class "M" lamps, regardless of manufacturer designation. Those lamps having substantially a 5 millisecond "lag" are designated as class "F" lamps. Accordingly, throughout the present specification and claims, these two different types of flashlamps will be referred to as class "M" and class "F" lamps; the class "M" lamps including those types having substantially a 20-22 millisecond "lag" and relatively long light-emitting characteristics, while the class "F" lamps include those types having a short or substantially 5 millisecond "lag" and a relatively steep light curve, or one of short duration.

Conventional flash synchronizers on the market today are only adjusted in accordance with

2

the "lag" characteristic of the different classes of lamps adapted to be used without any consideration as to shutter speed to be used. For instance, if a synchronizer is to be used only with class "M" flashlamps, it is usually adjusted to insure that the flash circuit will be closed in proper timed relation with operation of the shutter to insure the shutter being full-open when the lamp reaches its peak of illumination. Such adjustments are made to give this synchronization at the highest shutter speed of which the shutter is capable, because at these high speeds the shutter is open for the shortest time. However, when synchronizers so adjusted are used at the slower shutter speeds, that portion of the light emitted during the time that the lamp is coming up to peak is lost and the maximum light available is not used. With class "F" lamps, this loss of use of light at shutter speeds other than that which the synchronizer is adjusted for is not so important because of the steep or narrow nature of the light curves for these lamps. Those synchronizers which are adapted to accommodate both class "M" and class "F" lamps, as well as others, are usually adjusted between only two or more positions, depending upon the number of different class lamps to be accommodated, each adjustment being based solely on the "lag" characteristic of the lamps without regard to different shutter speeds which might be used.

While some shutters having built-in synchronizers adjustable by means of a scale to accommodate both class "M" and class "F" flashlamps include intermediate points on the adjusting scale by which the operator can make allowances for shutter speed to obtain a better light and speed combination than the synchronizer is primarily adjusted for, such adjustments are left to the judgment of the operator and require that he will be completely familiar with the burning characteristics of the class of lamps to be used, along with the opening characteristics of his shutter. Obviously, such adjustments are useful only to the advanced amateur or professional who takes the trouble to acquaint himself with the technicalities of shutter operation and lamp burning characteristics, and, even then, the adjustments he might make are only approximate and will not give the best possible light and speed combination.

One object of the present invention is to provide a built-in flash synchronizer in which the synchronizer is automatically adjusted by adjustment of the shutter speed control member to give the best possible light and speed combination for the class of flashlamp to be used.

Another object is to provide a built-in flash synchronizer of the type set forth which is adapted to accommodate both class "M" and class "F" flashlamps, and in which adjustment of the synchronizer according to the shutter speed is accomplished when using only one, or when using both classes of flashlamps.

A further object is to provide a built-in flash synchronizer of the type set forth which is adjustable to accommodate both class "M" and class "F" flashlamps, but in which further adjustment of the synchronizer as to shutter speed is accomplished only when using class "M" lamps and the operative connection between the shutter speed control ring and the synchronizer for making this last-mentioned adjustment is automatically made and broken as the synchronizer is adjusted to and from, respectively, a position to accommodate "M" class lamps.

And yet, another object is to provide in combination with a built-in flash synchronizer of the type described, including an electrical switch adapted to be operated by the shutter mechanism in proper timed relation with the opening of the shutter to produce the desired synchronization of light and shutter opening, and wherein the shutter is adjusted to vary the time of closing thereof in accordance with the class flashlamp used, an operative connection between the switch and speed control ring of the shutter by which the switch is further automatically adjusted in accordance with the selected shutter speed to give the best possible light and speed combination.

The novel features that I consider characteristic of my invention are set forth with particularity in the appended claims. The invention itself, however, both as to its organization and its methods of operation, together with additional objects and advantages thereof, will best be understood from the following description of specific embodiments when read in connection with the accompanying drawings, in which

Fig. 1 is a front elevational view of a complete photographic shutter having a built-in flash synchronizer constructed in accordance with the present invention;

Fig. 2 is a graph showing the characteristic light curve for class "F" and class "M" flashlamps, and showing an operating curve of the disclosed shutter superposed on the class "M" light curve to bring out the purpose and advantages of the novel adjustment of the synchronizer in accordance with the shutter speed that I provide to obtain the best possible light and speed combination for any selected shutter speed;

Fig. 3 is a front view of the shutter with the cover plate removed and showing the operative connection between the flash switch and the speed control ring of the shutter;

Fig. 4 is a front view of the shutter with the speed control ring removed and showing the cam ring for adjusting the synchronizer to accommodate different classes of flashlamps;

Fig. 5 is an enlarged detail of that part of the shutter including the scale for adjusting the synchronizer to accommodate different classes of lamps; and

Fig. 6 is an enlarged view of the shutter with the cover plate and other parts removed to show the blade-operating mechanism of the shutter, along with the flash synchronizer particularly adapted for this type of shutter-operating mechanism and in combination with which the present invention is adapted for use.

Like reference characters refer to corresponding parts throughout the drawings.

Referring, first, to Fig. 2, the purpose and result of the present invention will be described in connection with the graphs of this figure. Looking first at the characteristic light curve for class "M" flashlamps, it will be seen that for the first two milliseconds after the circuit of this class of lamp is closed, there is no appreciable light emitted, and then the amount of light increases quite gradually until the peak of illumination is reached at between 20-22 milliseconds. The peak remains at its maximum for not more than two milliseconds and then the light gradually falls off, taking more than 20 milliseconds to do so. In other words, this class of lamp is emitting some degree of light for over 40 milliseconds.

Superposed on this light curve of the class "M" lamps is a curve showing the operating characteristics of a photographic shutter of the type in connection with which my invention is disclosed. This curve is characteristic of all between-the-lens type shutters and differs from most in that it includes a $1/800$ speed, whereas most shutters only have a top speed of $1/200$, or $1/400$. The operating curve of the shutter is trapezoidal, the length of the top and bottom lines thereof varying with the speed of operation.

As indicated by the slope of the upright lines of the shutter curve, this shutter in question takes approximately two milliseconds to reach a full-open position after release and takes two milliseconds to close from a full-open position. The only exception to this is the $1/800$ speed setting where an additional spring is added to the blade-driving mechanism and the opening and closing times drop to about one and one-half milliseconds each.

Looking at the shutter curve it will be noticed that when operated at a speed of $1/25$ th second, the shutter is fully open for approximately 40 milliseconds, as indicated by the length of the top line bounded by the areas designated as brown. The full-open time of the shutter decreases as the speed increases until the $1/800$ speed is reached at which the shutter is only fully open for a little over one millisecond, this area being designated as red on the shutter curve. The full-open time of the shutter for the different speeds will vary with the speed as indicated on the curve; the $1/50$ speed being designated as purple, the $1/100$ speed as yellow, the $1/200$ speed as blue, and the $1/400$ speed as green.

It will be understood that in order to function with the greatest efficiency, or to obtain the maximum available light at the top or $1/800$ speed, the synchronizer must be adjusted so that the lamp will be at its peak during the one and one-half milliseconds that the shutter is fully open at this speed. Taking into account the one and one-half millisecond opening time of the shutter at this speed, this means that the synchronizer must be adjusted to close the lamp circuit about 19 milliseconds before the shutter is tripped. This is the basis upon which most synchronizers are selectively adjusted by the operator, since their adjustment is generally only to accommodate for different classes of flashlamps and not for shutter speeds in addition to the class lamp.

If the synchronizer when adjusted by the operator to use class "M" lamps is factory set to synchronize properly at only the $1/800$ or other top speed, it will be apparent from an inspection of Fig. 2 that if slower shutter speeds are used

with this class of lamp, a great amount of available light is lost and the device is not operating at the best possible light and speed combination. For example, if the synchronizer is adjusted to close the lamp circuit 19 milliseconds before the shutter is tripped, as is necessary to accommodate the $\frac{1}{800}$ speed, and the shutter is operated at a slower speed, then all or a part of the light emitted by the lamp, up until it reaches its peak, will be wasted, depending upon the shutter speed used because the shutter is not open during the time the lamp is reaching its peak. As a compromise, built-in synchronizers, adjustable to accommodate different classes of flashlamps, can be initially adjusted so that when set for class "M" lamps they will close the switch in timed relation to tripping of the shutter so as to bring the shutter to full-open position at the highest speed slightly ahead of the lamp reaching its peak. While this cuts down the maximum light available for operating at the highest shutter speed, it makes it possible for the slower speeds to get in more of the light under the rising portion of the light curve. Even with such a compromise, the best possible light and speed combinations are not approached. Looking again at Fig. 2, it will be observed that when a $\frac{1}{25}$ th shutter speed is used with class "M" lamps, the shutter is fully open so long that it could embrace almost the entire light output of the lamp if the delay time between switch operation and shutter tripping were reduced to 7 or 8 milliseconds. It also follows that in order to make use of the most available light at $\frac{1}{50}$ of a second shutter speed, the time delay should be 9-10 milliseconds; for a $\frac{1}{100}$ speed a 11-12 millisecond delay, and so on up to a maximum delay of 19 milliseconds for a $\frac{1}{800}$ shutter speed. My present invention comprises a means whereby conventional built-in synchronizers will be automatically adjusted by the selective setting of the speed ring of the shutter to attain the desired time delay between closing of the lamp switch and tripping of the shutter, giving the best possible light-speed combination.

Looking at the light curve of the class "F" lamps, it will be seen that this class of lamps reaches its peak of illumination rather quickly, about 5 milliseconds, and the useful light area under the curve is only about 12 milliseconds in duration. Accordingly, for practically all shutter speeds, except the $\frac{1}{800}$, if the shutter is tripped simultaneously with closing of the lamp switch, the shutter will be full-open to include the peak of illumination and will be open sufficiently long to make use of substantially all the available useful light. Because of the low light output of class "F" lamps, as compared with class "M" lamps, class "F" lamps would not ordinarily be recommended for use with shutter speeds as high as $\frac{1}{800}$ or $\frac{1}{400}$. Accordingly, I have found it desirable to correct the delay time of the synchronizer in accordance with the shutter speeds only when using class "M" lamps, although from the following description it will be obvious that the same adjustments could be provided and made available for class "F" lamps, as desired.

For purposes of disclosing my present invention I have shown it in combination with a built-in synchronizer of the type fully described in my copending application Serial No. 737,351, filed March 26, 1947, now Patent No. 2,563,782, issued August 7, 1951, and in a shutter having a blade-

operating mechanism of the type shown in my copending application Serial No. 728,528, filed February 14, 1947, now Patent No. 2,524,786, issued October 10, 1950. Inasmuch as the flash synchronizer and shutter blade operating mechanism are fully disclosed in my above-noted copending applications, only so much of the shutter blade operating mechanism and the flash synchronizer per se will be described herein as is necessary to point out the operation and purpose of the present invention.

The shutter, of which a synchronizer modified in accordance with my present invention forms a part, may appear as shown in Fig. 1. As indicated, the shutter may consist of an annular casing 1 having a cover plate 2 surrounding a central exposure aperture 3 and may contain the usual threaded flange 4 into which a front lens element, not shown, may be screwed in the usual manner. The shutter is preferably provided with a trigger 6 for releasing the blade driving mechanism and with a setting member 7 for tensioning the operating spring. The cover plate includes a speed scale 8 with which an index "P" on the face of a knurled flange 5 of a speed control ring 30, see Fig. 3, cooperates. The cover plate is also provided with a diaphragm scale 9 with which a pointer P' on the diaphragm adjusting ring, not shown, cooperates. The cover plate is also provided with a synchronizer adjusting means to make it possible for the operator to adjust the synchronizer for use with the different classes of conventional non-repetitive flashlamps having characteristic lags and for use with repetitive type flash lamps having no lag, as exemplified by lamps of the gaseous discharge type.

As shown, this synchronizer adjusting means comprises a setting member 10 which is fastened to an adjusting cam in the shutter, as will be described, and which extends upwardly through and moves in an arcuate slot 11 in the shutter cover. The cover adjacent this slot is provided with a graduated scale 11 carrying the letters "M," "F," and "X," with which the setting member cooperates. When the setting member is set opposite the letter "F" on scale 11, the synchronizer is adjusted for use with class "F" flashlamps, and when it is set opposite the letter "M" it is adjusted for use with class "M" flashlamps. When the setting member is set opposite the letter "X," the synchronizer is adjusted for use with gaseous discharge type flashlamps having no lag, but since this setting has nothing to do with the present invention, further description thereof and its functions will not be dealt with herein.

Essentially, the synchronizer, of which the present invention forms a part, comprises a switch associated with the shutter mechanism so as to be closed by operation of the shutter mechanism in proper timed relation with the opening of the shutter so as to synchronize the peak of the flash of the lamp with the full-open position of the shutter. Inasmuch as the flash synchronizer switch is associated with, and its operation is dependent upon, the operation of the shutter-operating mechanism, the shutter mechanism per se will be described herein sufficiently to point out the features of the synchronizer which are affected by the present invention. It is pointed out, however, that since the present invention is not limited to use with a shutter mechanism of the type described and said shutter mechanism is completely disclosed in my above-noted copending application Serial No. 728,528, only so much of

the mechanism per se will be disclosed herein as necessary to point out the operation of the flash synchronizer with which the present invention is combined.

As indicated in Figs. 4 and 6, the annular shutter casing may include an upstanding flange 15 extending around the periphery of the shutter; this flange having a slot 16 formed therein to permit movement of the setting lever and having a slot 17 permitting movement of the trigger 6 for tripping the shutter mechanism. As clearly set forth in my above-noted copending application, and as indicated in Fig. 6, shutter blades 18 are of the symmetrical type, each blade being pivoted at 19 to the mechanism plate 20 and having an upstanding pin 21 extending through an elongated slot 22 in an oscillatable blade ring 23. This blade ring directly carries an arm 1' which terminates in the setting member 7 and extends through the slot 16 in the flange 15. A power spring 25 is connected at one end directly to the blade ring 23 by a pin 26 and is connected at the other end to a stud "S" carried by the shutter casing. Thus, the spring 25 acts directly on the blade ring 23 and it becomes tensioned when the setting member 7 is moved clockwise to the position shown in Figs. 3, 4 and 6.

As indicated in Fig. 6, the blade ring is held with the spring tensioned by means of a latch mechanism which consists of a first latch member 28 pivoted on the stud 29 attached to the mechanism plate 20. The latch 28 has a beveled end 31 and extends across the top of the shutter; and this latch member lying beneath a second latch member 32 also pivoted on stud 29. Latch 32 has a latch face 33 adapted to engage an outwardly projecting protuberance 34 on the setting lever 7'. This latch therefore holds the setting lever 7' and the blade ring 23 in their set position when the lug 34 moves up over the incline 35 of the second latch member as the handle 7 is moved to a set position. A downwardly extending flange 36 limits the upward movement of the second latch member 32 under impulse of its spring 37, but it also permits the second latch to move downwardly with respect to its Fig. 6 position and the first latch member 28.

The first latch 28 includes the beveled surface 31, above referred to; which normally lies in contact with a beveled surface 38 on the shutter releasing member 39. This member may turn on a pivot 40 and includes a power spring 42 which by acting on pin 115 fixed to and extending above member 39 tends to turn member 39 in a counterclockwise direction. When the beveled surfaces 31 and 38 engage, movement of member 39 is prevented because the engagement of these two surfaces is almost on dead center between the studs 40 and 29 on which the power-operated member 39 and the first latch member turn. However, the trigger 6 can start movement of the first latch member 28 and which movement may then be completed by the power-operated member 39 in a manner completely disclosed in my copending application Serial No. 737,351, above mentioned. It will suffice herein to say that there is a connection between the trigger 6 and latch member 28 by which depression of the trigger 6 causes latch member 28 to be depressed sufficiently to move the beveled surface 31 out of dead center relation with beveled surface 38, but by an insufficient amount to actually trip the shutter. This further movement of latch member 28 is taken over by power-operated member 39 to actually release the shutter.

Coming now to the synchronizer with which the present invention is combined and which is fully disclosed in my noted copending application Serial No. 737,351, fastened to flange 15 of the shutter casing is a terminal 117 to which a mating connector on a flashholder, not shown, may be connected. The flashholder will include a source of potential and a flashlamp respectively, shown diagrammatically in Fig. 4 as "B" and "L," and the terminal is such that one side of the flash circuit will be grounded to the shutter casing, while the other side will be connected to the center post 117' of the terminal which is insulated from the shutter casing and extends to the interior thereof.

The switch for synchronizing conventional non-repetitive flashlamps having a "lag" comprises a first contact which is the pin 116 carried by the shutter release member 39 and a second and adjustable contact 115 lying in the path of movement of the pin 116. The contact 115 is carried by insulating member 200 which is, in turn, carried by an arm 113 pivoted on a stud 114 fastened to the mechanism plate of the shutter. The arm 113 has an upturned lug 201 thereon which engages a cam surface 112 on the synchronizer adjusting ring 100 which is oscillatably mounted in the shutter below the cover plate and speed control ring and which has the adjusting member 10 fastened thereto. Contact 115 is electrically connected to the center post 117' of terminal 117 by an insulated conductor 118 lying adjacent the interior of the flange 15 of the shutter casing and a conductor strip 203 fixed at one end to the conductor 118 and at the other end to a pin 204 on the arm 113. Conductor strip 203 is made of a resilient metal and takes the form of a coil spring so that it normally tends to pivot contact 115 in a counterclockwise direction and thus hold the lug 201 against the cam surface 112.

Therefore, inasmuch as contact 115 is connected to one side of the flash circuit through conductor 118 and pin 116 is connected to the other side of the circuit by being grounded through the shutter casing, when pin 116 engages contact 115 the flashlamp circuit will be closed to energize the lamp. Inasmuch as pin 116 is carried by the shutter releasing member 39, it can be made to engage contact 115 at any desired time prior to the actual release of the shutter and in accordance with the "lag" characteristics of the flashlamp to be used. To obtain the desired delay between closing of the lamp circuit and the release of the shutter, there is provided a gear-retarding mechanism including a flywheel 205 having a pinion 206 fixed thereto which, in turn, engages a gear segment 207 on the arcuate end of member 39. By adjusting the synchronizer ring 100 with the aid of member 10 and the scale 11, the position of contact 115 relative to that of pin 116 on member 39 can be varied to obtain a synchronization between the peak of illumination of the flashlamp and the full-open position of the shutter in accordance with class "F" and class "M" flashlamps. To allow the use of repetitive flashlamps of the gaseous discharge type which have no "lag," this synchronizer may include a second switch in series or parallel with the first switch which closes the instant the shutter blades reach their full-open position; means being provided to render the first switch inoperative when the second switch is used and this being accomplished by adjusting synchronizer cam ring 100 to the "X" position on scale 11. However, since

this second switch does not enter into the present invention, it will not be described herein.

Coming now to the present invention, for reasons fully discussed above it is desirable to be able to adjust the firing time of the flash switch in accordance with the shutter speeds to be used, particularly when using class "M" lamps. To accomplish this, I attach a cam plate 300 directly to the speed control ring 301 of the shutter to move therewith. As is customary in all between-the-lens type shutters, the speeds are determined by placing a retard action on the spring-driven blade operating member. As shown in Fig. 3, this is done in the present shutter by pivoting a double-ended lever 302 on the mechanism plate so that one end 303 thereof can move into the path of pin 26 on the blade-operating ring 23 and will have to be cammed out of the way by movement of the blade ring when moving through its operating stroke. The other end of lever 302 includes a gear segment 304 which meshes with a pinion 305 constituting one element of a gear train, the remainder of which is not shown. The farther the nose 303 of lever 302 is allowed to move into the path of the pin 26, the more retard action there is placed on the blade-operating ring and, hence, the slower the shutter speed. The position of the lever 302 is controlled by the speed control ring 301 which includes an opening 306 through which a pin 307 on the end 304 of the lever 302 extends; said opening having a stepped cam surface 308 against which the pin 307 is forced by a spring, not shown, normally acting to move lever 302 in a counter-clockwise direction. In other words, the steps on cam surface 308 determine the position of nose 303 of lever 302 relative to the path of travel of pin 26 on blade ring 23 and, consequently, the amount of retard action which is placed on the blade operating mechanism. As the speed control ring 301 is oscillated in accordance with the speed scale 8 on the cover plate 2, the proper step of cam surface 308 is moved opposite pin 307 to give this desired speed. As will be clear from an inspection of Fig. 3, when the speed control ring is set at $\frac{1}{400}$ or $\frac{1}{800}$ speed, the pin 307 will be confined in an arcuate portion 400 of the opening 306 so that the nose 303 of lever 302 will be removed entirely from the path of pin 26 on the blade ring and no retard action will be imposed on the blade mechanism. The difference between $\frac{1}{400}$ and $\frac{1}{800}$ speed is obtained in this shutter by the automatic inclusion of a booster spring for the $\frac{1}{800}$ speed, but, since this is not essential to the present invention, this is not shown.

Looking now at Figs. 3 and 4, the speed control cam 300 which is attached to the speed control ring 301 lies directly above the synchronizer adjusting ring 100 so that when the ring 100 is adjusted for class "M" lamps, the lug 201 connected to switch contact 115 extends upwardly sufficiently to engage cam 300. It will thus be seen that when the speed control ring is adjusted to give different shutter speeds, then cam 300 thereon will take over and adjust contact 115 relative to contact 116 to vary the closing time of the switch. This cam 300 is so calculated as to adjust the flash switch to give the desired and best possible speed and light combinations as discussed above. For instance, if the shutter is set for $\frac{1}{800}$ of a second speed, then the low point of the cam 300 will be opposite the lug 201 to allow contact 115 to move close to contact 116 and thus accommodate the maximum or 19-20 millisecond lag of the lamp. In this position, the cam 300 is coplanar with

cam 112 and is essentially inoperative. However, as the speed control ring is moved clockwise to give slower shutter speeds, cam 300 takes over full control of lug 201 and contact 115 from the synchronizer cam 112 and keeps reducing the delay time between switch closing and shutter release until at a $\frac{1}{25}$ speed the delay time is only about 7-8 milliseconds. In the position shown in Fig. 3, the speed control ring is adjusted for $\frac{1}{100}$ speed and cam 300 has adjusted contact 115 relative to contact 116 to give a 11-12 millisecond delay between closing of the flash switch and release of the shutter.

It will be observed that when the synchronizer cam ring 100 is adjusted to accommodate class "F" flashlamps that lug 201 of contact 115 is moved out of engagement with speed control cam 300 and is not affected by adjustment of the speed control ring. This is in accordance with the discussion above to the effect that because of the flash characteristics of this class of lamp, no adjustments as to shutter speed are really required. If it were decided, however, that such adjustments were needed, another speed cam, like cam 300 but with a different curve, could be added to the speed control ring to come into play when the synchronizer was adjusted for class "F" lamps. By virtue of the disclosed arrangement of parts, namely the disposition of cams 112 and 300, it will be apparent that speed control cam 300 will be automatically brought into operative relation with lug 201 when the synchronizer is adjusted by cam 112 to accommodate class "M" lamps.

While I have shown and described my invention in combination with a particular form of between-the-lens type shutter and having a particular form of built-in flash synchronizer, it will be readily understood that it could be applied to any form of flash synchronizer which is adjustable to accommodate the different classes of flashlamps. For instance, in U. S. Patent 2,319,086, Riddell, May 11, 1943, there is shown a built-in synchronizer including switch contacts 51 and 62, the former being adjustable relative to the latter through the use of cam 78 on control ring 77 to adjust the time of relative closing of the flash switch with the opening of the shutter blades to accommodate different classes of flashlamps. Furthermore, this patent shows a shutter and synchronizer combination wherein the flash switch is operated by the opening movement of the blade driving means, rather than by the operation of the shutter release mechanism. It will be obvious that the speed control ring of this shutter, not shown, could be provided with a cam, like cam 300 in the present disclosure, which would take over and further adjust upstanding finger 75 and, hence, switch contact 51 when control ring 77 was set for lamps having a 20-millisecond "lag" (class "M") and thus further adjust the switch to obtain the best possible speed and light combination for this class of lamps in accordance with the present invention.

Although I have shown and described certain specific embodiments of my invention, I am fully aware that many modifications thereof are possible. My invention therefore is not to be restricted except insofar as is necessitated by the scope of the appended claims.

Having thus described my invention, what I claim is new and desire to secure by Letters Patent of the United States is:

1. In a photographic shutter the combination with shutter blades; a blade operating mecha-

nism for controlling the opening and closing of said blades; a speed control member adapted to be selectively positioned to vary the speed of operation of a part of said blade operating mechanism involved in the actual opening and closing of the blades; a flash synchronizer mechanism comprising a normally open switch adapted to be connected into an electric circuit controlling the ignition of a flash lamp of the "F" class or "M" class; said switch arranged to be closed by a part of said blade operating mechanism in timed relation to the opening of said shutter blades thereby to accommodate for the "lag" of the flash lamp to be used; said switch being adjustable to alter the time of closing thereof relative to the blade opening movement of said blade operating mechanism; means for selectively adjusting said switch to adjust the time of closure thereof in accordance with the "lag" characteristic of either the "F" class or "M" class flash lamps; of means for further adjusting said switch to automatically alter the time of closure thereof in accordance with selected exposure speeds, and including mean operatively connecting said speed control member and said switch whereby said switch is adjusted by movement of said speed control member.

2. In a photographic shutter the combination with shutter blades; a blade operating mechanism for controlling the opening and closing of said blades; a speed control member adapted to be selectively positioned to vary the speed of operation of a part of said blade operating mechanism involved in the actual opening and closing of the blades; a flash synchronizer mechanism comprising a normally open switch adapted to be connected into an electric circuit controlling the ignition of a flash lamp of the "F" class or "M" class; said switch arranged to be closed by a part of said blade operating mechanism in timed relation to the opening of said shutter blades thereby to accomodate for the "lag" of the flash lamp to be used; said switch being adjustable to alter the time of closing thereof relative to the blade opening movement of said blade operating mechanism; means for selectively adjusting said switch to adjust the time of closure thereof in accordance with the "lag" characteristic of either the "F" class or "M" class flash lamps; of means for further adjusting said switch to automatically alter the time of closure thereof in accordance with the selected exposure speed when using lamps of the "M" class, said last mentioned means including means operatively connecting said speed control member and said switch whereby said switch is adjusted by and in accordance with movement of said speed control member; and means for automatically rendering said operative connection between said speed control ring and switch effective and ineffective as said first mentioned or selective switch adjusting means is moved to and from, respectively, the position to accommodate "M" class lamps.

3. In a photographic shutter the combination with shutter blades; a blade operating mechanism for controlling the opening and closing of said blades; a speed control member adapted to be selectively positioned to vary the speed of operation of a part of said blade operating mechanism involved in the actual opening and closing of the blades; a flash synchronizer mechanism comprising a normally open switch adapted to be connected into an electric circuit controlling the ignition of a flash lamp of the "F" class or

"M" class; said switch comprising a pair of normally spaced contacts, one of said contacts adapted to be engaged and moved into switch closing relation with the second contact by a part of said blade operating mechanism when moving to open the shutter, means for selectively adjusting said second contact relative to the first contact to alter the time of closing of said switch in accordance with the "lag" characteristics of class "F" or class "M" lamps; of means for further adjusting said second contact to automatically alter the time of closure thereof in accordance with selected exposure speeds, and including a cam means moved by said speed control member and having its curve operatively engaging said second contact to adjust said contact as said speed control member is moved.

4. In a photographic shutter the combination with shutter blades; a blade operating mechanism for controlling the opening and closing of said blades; a speed control member adapted to be selectively positioned to vary the speed of operation of a part of said blade operating mechanism involved in the actual opening and closing of the blades; a flash synchronizer mechanism comprising a normally open switch adapted to be connected into an electric circuit controlling the ignition of a flash lamp of the "F" class or "M" class; said switch comprising a pair of normally spaced contacts, one of said contacts adapted to be engaged and moved into switch closing relation with the second contact by a part of said blade operating mechanism when moving to open the shutter, means for selectively adjusting said second contact relative to the first contact to alter the time of closing of said switch in accordance with the "lag" characteristics of class "F" or class "M" lamps; of means for further adjusting said second contact to automatically alter the time of closure of said switch in accordance with selected exposure speeds when said selective switch adjusting means is positioned to accommodate class "M" lamps, and including a cam carried by said speed control member to move therewith, the curve of said cam operatively engaging said second contact to control movement thereof relative to said first contact.

5. In a photographic shutter the combination with shutter blades; a blade operating mechanism for controlling the opening and closing of said blades; a speed control member adapted to be selectively positioned to vary the speed of operation of a part of said blade operating mechanism involved in the actual opening and closing of the blades; a flash synchronizer mechanism comprising a normally open switch adapted to be connected into an electric circuit controlling the ignition of a flash lamp of the "F" class or "M" class; said switch comprising a pair of normally spaced contacts, one of said contacts adapted to be engaged and moved into switch closing relation with the second contact by a part of said blade operating mechanism when moving to open the shutter, means for selectively adjusting said second contact relative to the first contact to alter the time of closing of said switch in accordance with the "lag" characteristics of class "F" or class "M" lamps; of means for further adjusting said second contact to automatically alter the time of closure of said switch in accordance with selected exposure speeds when said selective switch adjusting means is positioned to accommodate class "M" lamps, and including a cam carried by said

speed control member to move therewith, the curve of said cam operatively engaging said second contact to control movement thereof relative to said first contact, and means for automatically connecting and disconnecting said operative engagement between said cam and second contact when said selective switch adjusting means is moved to and from, respectively, the position to accommodate class "M" lamps.

6. In a photographic shutter the combination with shutter blades; a blade-operating mechanism for controlling the opening and closing of said blades; a speed control member adapted to be selectively positioned to vary the speed of operation of a part of said blade-operating mechanism; a flash synchronizer mechanism comprising a normally open switch adapted to be connected into an electric circuit controlling the ignition of a flash lamp having a characteristic "lag"; said switch arranged to be closed by a part of said blade-operating mechanism in timed relation to the opening of said shutter blades thereby in order to accommodate for the "lag" of said flash lamp; said switch being adjustable to alter the time of closing thereof relative to the blade-opening movement of said blade-operating mechanism; of means for adjusting said switch to automatically alter the time of closure thereof in accordance with the selected exposure speed, and including a cam connected to said speed control member to be moved by adjustment thereof, said cam directly engaging a part of said switch to adjust the time of closing thereof.

7. In a photographic shutter the combination with shutter blades; a blade-operating mechanism for controlling the opening and closing of said blades; a speed control member adapted to be selectively positioned to vary the speed of operation of a part of said blade-operating mechanism; a flash synchronizer mechanism comprising a normally open switch adapted to be connected into an electric circuit controlling the ignition of a flash lamp having a characteristic "lag," said switch comprising a pair of normally spaced contacts, one of said contacts adapted to be moved into engagement with the second by a part of said blade-operating mechanism to close the switch in timed relation to the opening of said shutter blades in order to accommodate for the "lag" of said flash lamp; said switch being adjustable to alter the time of closing thereof relative to the blade-opening movement of said blade-operating

- mechanism; of means for adjusting said switch to automatically alter the time of closure thereof in accordance with the selected exposure speed, and including a cam connected to said speed control member to be moved by adjustment thereof, said cam connected to the second contact of said switch to adjust the separation between it and said first contact to alter the time of closing thereof.
8. In a photographic shutter of the setting type the combination with shutter blades; a blade-operating mechanism for controlling the opening and closing of said blades when moving from a cocked condition; a release mechanism for releasing said blade-operating mechanism from its cocked condition; a speed control member adapted to be selectively positioned to vary the speed of operation of a part of said blade-operating mechanism; a flash synchronizer mechanism comprising a pair of normally spaced switch contacts adapted to be connected into an electric circuit controlling the ignition of a flash lamp having a characteristic "lag"; means for connecting one of said switch contacts to said release mechanism to be moved into engagement with the second contact upon movement of said release mechanism to a shutter-releasing position and in timed relation with the release of said blade-operating mechanism thereby; of means for automatically altering the relative time of closing of said switch and the release of said blade-operating means by said release mechanism to accommodate for the "lag" of the flash lamp and the selected exposure speed, and including an operative connection between said speed control member and the synchronizer mechanism whereby the time of closing of said switch relative to the release of said blade-operating mechanism from a cocked condition is automatically adjusted by movement of said speed control member.

CARL C. FUERST.
